UNITED STATES PATENT OFFICE

JOHN BENNER, OF PHILADELPHIA, PA., ASSIGNOR TO AMERICAN STOVE
AND HOLLOW-WARE COMPANY, OF SAME PLACE.

DESIGN FOR STOVE.

Specification forming part of Design No. **7,514**, dated June 30, 1874; application filed June 10, 1874.
[Term of Patent 7 years.]

To all whom it may concern:

Be it known that I, JOHN BENNER, of the city of Philadelphia, in the county of Philadelphia and State of Pennsylvania, have invented a Design for Stove-Castings, (heating-stoves,) of which the following is a specification:

The nature of my design or invention is fully represented in the accompanying photographic illustration, to which reference is made. Stoves of the class to which these castings belong are usually made up with sheet-iron bodies.

Figure 1 shows the base and feet of a small coal-stove; Fig. 2, the door-frame and door; and Fig. 3 the top casting for the same.

The main body of these castings have a plain smooth surface, with moldings, curves, and inclinations, as shown, while a higher degree of ornamentation is obtained by the small carved figures of several kinds, *a b c d*, arranged and disposed as shown.

I claim as my invention—

The design for a stove, consisting of the moldings, curves, and inclinations, combined with the small carved figures *a b c d e*, arranged and disposed as shown.

JOHN BENNER.
